UNITED STATES PATENT OFFICE.

CLARENCE A. STEERE, OF WICKFORD, RHODE ISLAND, ASSIGNOR TO CROMPTON & KNOWLES LOOM WORKS, OF WORCESTER, MASSACHUSETTS, A CORPORATION OF MASSACHUSETTS.

LET-OFF AND TENSION MECHANISM FOR NARROW-WARE LOOMS.

Application filed May 15, 1925. Serial No. 30,569.

This invention relates to a let-off mechanism for a narrow ware loom. It is the general practice in such looms to provide a separate beam or spool for each separate narrow fabric in the loom. This involves much duplication of parts, with corresponding increase in cost, and also requires the winding of a considerable number of separate warp beams for each narrow ware loom. It is the object of my invention to provide a let-off mechanism so designed that a number of narrow warp sections may be taken from a single wide warp beam and that each warp section may be separately tensioned and adjusted.

It is a further object of my invention to provide a construction by which slackness in any warp section may be easily taken up and the tension restored independent of every other warp section. This is particularly advantageous when a defect in weaving a particular narrow fabric necessitates a pick out of more or less length.

My invention further relates to arrangements and combinations of parts which will be hereinafter described and more particularly pointed out in the appended claims.

A preferred form of the invention is shown in the drawings, in which

Fig. 1 is a side elevation of parts of a loom embodying my invention;

Fig. 2 is a rear elevation of the parts shown in Fig. 1; and

Fig. 3 is a front elevation of the differential pulley, partly in section along the line 3-3 in Fig. 1.

Referring to the drawings, I have shown a portion of a narrow ware loom having a frame 10 on which a warp beam 11 is supported in bearings 12. The warp beam 11 is provided with friction drums or pulleys 13 at its ends, engaged by friction bands 14. One end of each friction band is adjustably secured to a bracket 15 on the loom frame 10 and the other end of the band is pivotally connected at 16 to a lever 17 having a guide roll 18 pivoted at its outer end.

A second guide roll 19 is rotatably mounted in fixed arms 20 secured to the loom frame and a third guide roll 21 is pivotally mounted at the outer end of levers 22, which levers are pivoted to the loom frame. Any desired number of weights W may be hung on the

outer ends of the levers 22. A fourth guide roll 24 is pivoted in fixed bearings 25 above the loom.

A series of grooved pulleys or sheaves 30 are mounted in separate bearing members 31 in which they are freely rotatable. Each bearing member 31 is supported by a rope or other flexible member 32 which passes over a fixed guide pulley 33 to a second bearing member 34 provided with a second sheave 35. The guide rolls 33 are mounted on fixed brackets 36 (Fig. 2) suitably secured above the loom.

A differential pulley 40 for each sheave 35 is mounted between the collars 41 (Fig. 3) on a fixed shaft 42 secured in brackets 43 (Fig. 1) fastened to the loom frame 10. The pulley 40 is provided with a larger drum portion 44 and a smaller drum portion 45 and is also provided with a radial recess 46 in which is disposed a friction block 47 and an adjusting screw 48.

A rope 50 passes around the sheave 35 previously described and has its two ends secured in flanges on the differential pulley 40, so that one end portion of the rope will be wound in one direction on the larger drum 44, while the other end portion of the rope will be wound in the opposite direction on the smaller drum portion 45.

A separate sheave 30, rope 32, sheave 35, differential pulley 40 and rope 50 are provided for each section S of warp on the warp beam 11.

Having described the construction of my improved let-off and tension mechanism, the method of use and the operation thereof are as follows: The warp threads for each separate narrow fabric, such as a tape or ribbon, form a separate warp section S on the warp beam 11. All of these warp sections are led from the warp beam 11 around the upper fixed guide-roll 24 and back to the lower fixed guide roll 19. The warp sections S then pass successively around the movable guide rolls 18 and 21 and then pass upward to the sheaves 30.

Each warp section S passes over its individual sheave 30 and then passes downward to a guide bar or whip roll 60 (Fig. 1), from which point it is led forward through the harnesses to the fell of the fabric. When a new warp is placed in the loom, the sheaves

30 are lowered to positions somewhat closely adjacent to the guide roll 24. This is accomplished by moving the rope 50 in such a direction as to wind the rope off of the large drum and on to the small drum, thus lengthening the free portion of the rope and permitting the sheave 35 to rise and the sheave 30 to be lowered.

The loom is then placed in operation and the tension on the warp is regulated by the weights W. The let-off action of the beam 11 is intermittent, as the warp pulls the weighted levers 22 upward until the levers 22 engage and lift the levers 17, thus releasing the friction on the warp beam.

The beam immediately starts to revolve and lets off a certain amount of warp, so that the levers 17 and 22 will swing downward. Such action restores the friction on the brake beam 11 and also provides a certain amount of free motion for the levers 22 before the levers 17 are again lifted to release the friction. This intermittent let-off mechanism is of a usual type and in itself forms no part of my invention.

With the loom operating as described, let it be assumed that a defect occurs in one of the narrow fabrics and necessitating a pick out of considerable length. It is obviously impossible to turn the beam 11 backward, as a number of other warp sections on the same beam cannot be let back. At the same time slack warp has been produced in the section under repair and it is absolutely necessary for this slack warp to be taken care of.

To accomplish this result, the operator merely pulls on the rope 50 in the direction of the arrow *a*, winding the rope off of the small drum and on to the large drum and thus shortening the free portion of the rope. This draws the sheave 35 downward and raises the sheave 30 to restore the desired warp tension to the warp section under repair, after which the loom continues to operate as before. The friction block 47 in the differential pulley is adjusted to hold the pulley 40 by friction in any desired position.

I have thus provided a very simple arrangement by which the tension of any separate warp section may be adjusted as desired, independently of all other warp sections. The sheaves 30 are purposely placed as far as possible from the guide roll 21, so that the warp threads may be collected in the sheaves 30 without causing noticeable change of tension in the different threads,

due to the angles from which they approach the sheaves 30.

Having thus described my invention and the advantages thereof, I do not wish to be limited to the details herein disclosed otherwise than as set forth in the claims, but what I claim is:—

1. A narrow ware loom, having in combination a warp beam containing warp for several warp sections for separate fabrics, let-off mechanism for said warp beam, and manually operable rotative means effective to positively change the path of travel of any selected warp section, and to definitely determine the length of said path between the warp beam and the fell of the fabric for any selected warp section.

2. A narrow ware loom, having in combination a warp beam containing warp for several warp sections for separate fabrics, let-off mechanism for said warp beam, and manually operable rotative means effective to positively change the path of travel of any selected warp section, and to definitely determine the length of said path, manual means to positively vary and determine the length of warp between the warp beam and the fell of the fabric for any selected warp section, said means comprising a guide member for each warp section engaging the warp between the let-off mechanism and the fabric, and manual means to change the position of any selected guide member to a different definite position and to hold said member in its new position.

3. A narrow ware loom, comprising a let-off and tension mechanism as set forth in claim 2, in which said manual means includes a sheave, a differential pulley, a rope having its ends reversely secured to said pulley and its middle portion engaged by said sheave, and a connection from said sheave to said guide member.

4. A narrow ware loom, comprising a let-off and tension mechanism as set forth in claim 2, in which said manual means includes a sheave, a differential pulley, a rope having its ends reversely secured to said pulley and its middle portion engaged by said sheave, and a connection from said sheave to said guide member, and in which a friction device is provided effective to yieldingly hold said differential pulley from rotation.

In testimony whereof I have hereunto affixed my signature.

CLARENCE A. STEERE.
